(57) **CLAIM**

The ornamental design for a joined universal bellow, as shown and described.

DESCRIPTION

FIG. 1 is a top, front perspective view of a joined universal bellow with the tabs in an open position;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front, left side perspective view of the joined universal bellow with the tabs in a folded position;

FIG. 9 is a top, front perspective view thereof, shown with one tab folded; and,

FIG. 10 is a back view thereof, shown with one tab folded. The broken lines shown in FIG. 7 illustrate portions of the joined universal bellow that form no part of the claimed design. The broken lines shown in FIG. 8 illustrate environment and form no part of the claimed design.

1 Claim, 8 Drawing Sheets
